UNITED STATES PATENT OFFICE.

CHARLES L. TRAVIS, OF MINNEAPOLIS, MINNESOTA, ASSIGNOR TO THE
MINNEAPOLIS GRAIN BINDER COMPANY.

GRAIN-BINDER.

SPECIFICATION forming part of Letters Patent No. 243,828, dated June 21, 1881.

Application filed November 21, 1879.

To all whom it may concern:

Be it known that I, CHARLES L. TRAVIS, of Minneapolis, in the county of Hennepin and State of Minnesota, have invented certain Improvements in Grain-Binding Machines, of which the following is a specification.

This invention relates to that class of binding-machines in which cord is employed as the binding material, and fastened by tying the ends of the applied band together; and it consists more particularly in improvements in the machine for which Letters Patent were granted to me bearing date June 3, 1879, No. 216,241, although certain of the features are applicable also to other machines.

The principal objects of the present invention are to secure the tightening of the band upon the bundle, to render the formation and tightening of the knot a matter of certainty, and to simplify the machine.

With these ends in view the invention consists in a peculiar manner of constructing the parts so that the cord to form the knot is drawn from the band upon the bundle and the knot tied without permitting the band to slacken; also, in arranging the knife and holder by which the cord is severed and held directly beneath the rotary tying-head, to retain the cord directly beneath and in position to enter said head; also, in a clamp located between the knife or equivalent cord-retaining device and the tying-head, to assist in holding and presenting the cord; also, in a movable arm or jaw located below the tying-head to assist in bringing the cord in the proper relation to the tying-head; also, in a device of peculiar construction and arrangement to assist the binder-arm in presenting the cord across the center of the tying-head; also, in the manner of actuating the cord cutting and clamping knife; also, in a tension device embracing a flat bearing-surface and an elongated spring bearing lengthwise upon the cord and rounded gradually upward at one end to its point of support; also, in various minor details, herein-after described.

Referring to the accompanying drawings, Figure 1 represents a sectional elevation of the machine on the line of the binder-arm, which latter is shown in a descending position; Fig.

2, a similar view with the binder-arm in its lowermost position and the two ends of the band grasped by the tying devices; Fig. 3, a longitudinal vertical section on the line *y* *y*, Fig. 1, showing the manner in which the ends of the band are presented to and held by the tying mechanism; Fig. 4, a plan view, showing the cord holding and tying devices with the covering-plate removed; Fig. 5, a perspective view of the machine with the binding-table and covering-plate of the tying mechanism removed in order to expose the latter, the parts being shown in the positions which they occupy at the completion of the loop in the ends of the applied band; Fig. 6, a perspective view of the tying-fingers and their carrying-shaft; Fig. 7, a perspective view of one end of the binding-table and the device for raising or moving the bundle to tighten the knot. Fig. 8 is a longitudinal central section of the tying-head, showing the link-connection by which the pivoted tying-finger is actuated. Fig. 9 is a cross-section of the same on the line *x* *x*; Fig. 10, a rear view of the same.

In its general construction and mode of operation the present machine resembles the one described in my former patent, hereinbefore alluded to, a vertically-vibrating binding-arm serving to carry the cord around the bundle and present it to a rotary head having two transverse fingers or nippers, which twist the ends of the band into a loop and then draw the extreme ends through said loop to form the knot. A rotary knife also serves, as in the original machine, to sever the applied band and retain the newly-formed end.

A represents the bed-plate or base-frame of the machine, containing at one end all the cord retaining and tying devices, and *B* represents the grain receiving or binding table, which may be made either flat or concave, as preferred, and which is, by preference, arranged flush with the top of the base-frame. At one end the base-frame is provided with an upright rigid overhanging arm, *C*, sustaining the horizontal rock-shaft *D*, to one end of which the curved binder-arm *E* is rigidly secured. The binder-arm is made of such length that when turned down its end passes beneath all the tying and clamping mechanism, as shown in Figs. 1, 2, 100

and 5. The arm is slotted at its end to receive the binding-cord and provided with two pulleys, between which the cord passes loosely, as shown, and, as usual in this class of machines, the binding-table is slotted to permit the binding-arm to pass through the same, beneath the grain, to the tying mechanism. The outer end of the binder-arm shaft D is provided, as in the original machine, with a slot-
10 ted arm actuated by a lever and crank in such manner as to cause the arm to swing upward and downward and pause for a short period at the end of the downward movement.

The rotary tying-head, which revolves in a vertical plane and is similar in its general construction and mode of operation to that in the original machine, consists of two rotating and laterally-moving knotting-fingers, and a surrounding sleeve fixed against end movement
15 to hold the cord in the proper position to be acted upon by the fingers.

Referring to the drawings, F represents the external tube or sleeve, mounted loosely in bearings so that it may rotate, and provided
20 with a circumferential groove, into which a fixed key or plate, a, extends, as shown, so as to prevent the sleeve from moving endwise.

G represents the main tying-finger, formed by cutting away, in the manner shown in Fig.
25 30 6, the end of a round shaft, H, which has said end mounted in the sleeve F, as shown in Fig. 3. As shown in Figs. 1, 2, 3, and 6, the finger extends diametrically across the end of the shaft, at a short distance therefrom, so that the
35 40 cord may be passed between them. The outer side of the finger G is grooved or recessed lengthwise to receive the second and smaller finger, I, which is pivoted therein, at or near the middle, and arranged to open and close at the proper times in order to grasp and hold the ends of the cord.

An important improvement in the device consists in cutting away, as shown in Fig. 6, one side of the finger G at the free end of
45 50 the small finger I, thereby producing a small groove or space, k, into which the ends of the cord may seat themselves as the loop is drawn over them in forming the knot.

In the original machine and others of its class, the ends of the cord laid upon the outside of the fingers, in front of the loop, and offered a strong resistance to the escape of the loop over the ends of the fingers, so that the enlargement of the loop and the application of a
55 60 strong force was required in forming the knot. By permitting the ends of the cord to close down within the fingers, as in the present device, the loop is permitted to pass over them and escape from the fingers quickly and easily and without being enlarged, thus securing the formation of the knot with less power and in a tighter manner than usual. The movement of the fingers in a direction lengthwise of the sleeve F is secured by mounting the shaft H
65 70 of the finger G in bearings on a horizontally-reciprocating plate, J, the movement of which causes the two fingers to move outward beyond

the forward end of the sleeve, as shown in Fig. 4, so as to admit the cord behind them, and then move backward into the sleeve, as shown in Fig. 3, so as to bend or kink the cord preparatory to twisting the same into a loop. The fingers receive an intermittent rotary motion through a pinion, K, applied to the rear end of the shaft H, and acted upon by a mutilated gear-wheel, L, as shown in Figs. 4 and 5.

For the purpose of drawing and holding the cord, when presented by the binder-arm, against the end of the sleeve F, I form upon or attach to the end of the sliding plate, J, a horizontal hooked arm or jaw, M, which moves forward and backward with the plate, so that the cord, being laid inside of the same by the binder-arm, is drawn back as the fingers recede, and held against and across the end of the sleeve in the manner shown in Figs. 2, 3, and 5.

The arm and its actuating devices may be made independent of the sliding plate, if desired; but the arrangement shown is considered the best.

In order to hold the ends of the applied band during the formation of the knot, and retain the cord during the interval which occurs between the action of the successive blades of the knife, 95 a jaw, N, is arranged opposite the arm M, so as to bear against the cord as the latter is forced inward by the arm or jaw M. The jaw or clamp N may be made rigid, if desired; but it is preferred to have it yield under the pressure of the arm M, for the reason that it will then have less tendency to cut or weaken the cord, and also because it will grasp the ends sooner. The jaw N may be made elastic, or may be arranged to slide and urged outward by a spring, as shown in the drawings. If preferred, the jaw N may be rigid, and the arm M arranged to yield under pressure. The parts M N act before the formation of the knot in the cord, and before the applied band is severed from the main cord, so as to retain the cord in the time that one knife-arm is succeeding the next.

O represents the cutting and clamping knife, located beneath the parts M N on the under side of a rigid plate, P. The knife is constructed with four radial cutting-arms, which act successively in connection with plate P to sever the cord. Beneath the knife, in an extension of plate P, there is pivoted an eccentric, Q, urged upward by a spring, R, so as to retain the cord. The construction and operation of the knife are essentially the same as in the patent granted to Olmsted, Travis, and Chute, dated April 23, 1878, No. 202,747. The location of said devices, however, in the present instance, directly beneath the tying-head is a feature of importance, since they are thereby enabled the better to grasp the cord and hold the same in the required position.

An important feature of the present invention is the manner of imparting the intermittent rotation to the knife, which is by means of a vertically-revolving arm, R', as shown in

Fig. 5, which acts upon the arms of the knife one after another, imparting to the knife at each action a quarter-revolution, causing one arm or blade to succeed the next, and sever and hold the cord. It will of course be understood that the knife acts but once during the binding of each bundle.

The knife-operating arm may be driven in any suitable manner, but in the present instance is mounted on a bottom shaft, S, which also carries the cam and gear-wheel for actuating the tying-head.

In order to assist the binder-arm in presenting the cord across the center of the tying-head behind the fingers, I provide said arm, as shown in Figs. 1, 2, and 5, with a supplemental arm or finger, T, pivoted at its rear end in a slot in the binder-arm and arranged to close down when not in action into said arm. The free end of the finger T is notched to fit over the cord and provided with a side lip, which closes into a notch in the arm to prevent the finger from falling through the same. The finger is pivoted to the lower end of a rod, b, which is acted upon at its opposite end by a spring, c, attached to the binder-arm, in order to hold the finger T normally in a closed position within the binder-arm. The upper end of the rod b is provided with a side pin, d, and the standard C provided with a rigid arm, e, to act upon the pin d as the binder-arm descends in carrying the band around the bundle, and thereby raise the finger T from the binder-arm, so that it will pass above the tying-head, as shown in Fig. 2. The finger T in thus rising lifts the cord in such manner that it extends in a vertical direction from the eye or rollers of the binder-arm to the end of the finger, whereby said parts are caused to carry it behind or inside of the finger G, directly across the center of the head.

On the top of the base frame or plate, at the point where the band leaves the grain, I place an upwardly-rounded rest or rib, U, as shown in Figs. 1 and 2, which serves to sustain and support the cord during the operation of tightening the band, and prevent it from chafing and cutting against the edge of the slot or throat.

As a means of tightening the knot before the discharge of the bundle, I provide for raising the latter after the formation of the knot and before the tying-fingers release their hold. Any suitable device may be used for this purpose; but a simple and effective contrivance is that shown in the drawings, consisting of an arm or lever, W, pivoted to the side of the base-frame and bent at right angles across the end of said frame, as shown in Figs. 3, 4, and 7. At its inner end the arm is extended downward to connect with a cam-wheel, X, by which the arm is vibrated in a vertical direction. During the binding of the bundle the end of the arm W remains down level with the table or base-frame beneath the bundle; but after the formation of the knot it rises and lifts the bundle. The cam X is mounted on the same

shaft that carries the other cams and the driving-gear of the machine.

In the practical operation of the machine it is desirable that the cord shall receive a uniform tension, and it is therefore necessary to employ a tension device through which knots and other inequalities may pass without affecting its action. This result I secure, as shown in Fig. 1, by the employment of an adjustable tension-spring, Y, of flat form, bearing lengthwise for a considerable distance upon the cord. The cord bears below upon a flat surface, and the spring, which is raised and fastened at one end, bears on top of the cord over a considerable surface. The gradual elevation or upward curvature of the spring at one end is of importance, since it permits the knots and other great irregularities to enter and pass easily. Whenever a knot or thickened portion passes beneath the spring it lifts the same and decreases its bearing-surface, but at the same time increases its tension and pressure sufficiently to compensate therefor, and thus the tension is equalized. As shown in the drawings, the tension-spring is applied to a vertically-vibrating arm, Z, which serves to guide the cord and take up slack therein, as usual.

I am aware that it is old to use flat pressure-springs having a narrow bearing on the cord or thread; also, that one flat plate has been drawn against another by means of a stem and an adjustable spring, and therefore I do not claim either of said constructions. My device differs from others in that the spring itself forms the bearing-surface, that the bearing is a very extended one, and that at the receiving end the spring curves gradually upward, so that the knots and enlargements, which are frequently three or more times the diameter of the cord, can enter beneath the spring easily and gradually without causing any sudden strain or shock. Two eyes, g, on the arm Z guide the cord, and the spring is secured to one of said eyes and passed loosely through the other, which is provided with a pressure-screw, h, bearing on the spring. The spring may be otherwise located and may be changed in form, provided the mode of action is retained.

The machine, being constructed as above described, is attached in any suitable manner to a harvesting-machine, and the grain delivered within reach of the binder-arm by means of elevating-aprons, as shown in the drawings, or otherwise. The cord being passed from the spool or ball through the tension devices and take-up, and thence through the binder-arm to the clamping devices beneath the tyer-head, the action is as follows: The binder-arm E swings downward and carries the cord around a sufficient quantity of grain to form a bundle. As the binder-arm completes its downward movement the finger T rises above and advances over the tying-head, thereby raising the cord and acting in connection with the binder-arm to carry the two ends of the applied band vertically across the center of the tying-head,

inside of or behind the main tying-finger G, which at this time stands outward in advance of the sleeve F. At the same time that the cord is thus laid behind the finger G it is presented, as shown, across the end of the sleeve F. As soon as the above operation is completed the binder-arm comes to a rest, the two fingers draw backward into the tube, bending the cord back therein loosely behind them, and 10 at the time that this action commences the jaws M N clamp the two ends of the cord forming the applied band firmly together. The fingers, still having the cord bent loosely behind them, as stated, then revolve and thereby 15 wind the cord around them into a loop, the portion of the cord which forms the loop being taken from between the clamp and the grain, so that the band is tightened upon the bundle or sheaf. As the fingers approach the 20 end of the first revolution and complete the formation of the loop, the small outside finger I opens outward to grasp the cord below the loop, between the latter and the clamp. The fingers, continuing their rotation with the cord 25 loosely behind them, crowd the loop upward toward the bundle, and then the finger I, at or about the end of the first rotation, closes firmly upon both cords, and the two fingers, without separating, move out of the tube. The knife 30 then severs the applied band from the main cord and retains the newly-formed end, and at the same instant the clamp releases the ends, and the continued rotation of the fingers, which hold the cord firmly between them, 35 causes the ends in a looped form to be drawn tightly into the first or main loop in such manner as to form a bow-knot. The fingers retain their hold until they reach an upright position at the end of one and a quarter revolution, 40 when they separate to release the looped end from between them; but just before this takes place the arm W rises and lifts the bundle, so as to tighten the knot with additional firmness, so that there may be no chance of its slipping or loosening under any circumstances. 45 The action of the lifting-arm continues until the knot is drawn from the tyer and the bundle released. The firm hold of the fingers continues in every instance until the knot has 50 been completely formed and drawn close, so that the band cannot slacken under the strain of the grain.

A special advantage of my tyer consists in the fact that it ties the knot close to the grain, 55 and that in the tightening of the knot the slack is taken up toward instead of away from the bundle. This is due to the fact that the ends of the band are clamped firmly during the formation of the loop, and that the ends to be 60 drawn through the loop are seized firmly by the knotting-fingers before the knotting devices cease to act, and held by the fingers until the knot is drawn close. A clear distinction must be made between my device, which 65 holds the ends firmly and draws them through the loop to form a bow-knot, and those devices which hook loosely upon the ends and draw

them loosely through the loop, leaving the parts in position to form a hard knot when the band expands so as to tighten the loop. 70 In my case the fingers tighten the knot. In the other the knot is tightened by the expansion of the bundle and band taking up the cord which forms the loop and drawing the same around the ends. 75

I do not claim herein the described method of applying and securing bands upon grain-bundles, consisting in clamping the two extreme ends of the applied band in a fixed position, winding the ends between the clamp and 80 the bundle into a loop, grasping the strands between the fixed clamp and the loop, releasing the ends from the fixed clamp, and drawing them positively through the loop into a close knot; nor do I claim herein the combination 85 of a grain-support, fixed clamping device to hold the ends of the band, rotating and longitudinally-moving fingers located between the 90 clamp and the grain-support, and operating mechanism, whereby the parts are caused to carry out the method of tying above described, 95 the present invention being limited as regards the method of and devices for tying the knot to those matters which are specifically claimed herein; neither do I claim, broadly, herein, 100 means for moving the bundle while the knot-tying devices retain their hold upon the band for the purpose of drawing the knot tight with a positive action, it being my design to make the same the subject of a separate application, 105 and the invention, in the present case, being limited to the peculiar construction and arrangement of devices herein described and claimed; neither do I claim herein the link-connection between the pivoted tying-finger 110 and its actuating-bar, as this feature will also be made the subject-matter of a separate application. 115

As to all matters and things which may be shown or described, but which are not specifically claimed herein, the right is reserved to make them the subject of claims in future patents, the present invention being limited to the matters claimed. 120

What I claim as my invention is— 125

1. The combination of the external tube and the rotary fingers lying transversely to the axis of the tube and arranged to move into and out of the same, as described, the construction being such that an open space for the free passage of the cord exists around and behind the fingers when they are within the tube. 130

2. In a tying device, the combination of an external tube or sleeve and two rotating tying jaws or fingers adapted and arranged to move lengthwise of the sleeve into and out of the same, and to leave a free and open space around and behind them when they are within the tube. 135

3. The combination of a clamp which holds firmly the two parts of the applied band, a sleeve or tube fixed against end motion, a band-carrier adapted to present both parts of the band across the mouth of the tube, and two 140

- rotating and longitudinally-moving fingers arranged to draw within the tube and carry the two parts of the band therein without thereby clamping or binding said parts or ends.
- 5 4. The combination of the outside tube fixed against end motion, the two rotating longitudinally-moving fingers arranged to pass into the tube, and the jaw or clamp M, arranged to force and hold the two parts of the applied 10 band across the mouth of the tube previous to the passage of the fingers therein.
5. In a grain-binder, the combination of a rotary tying-head, a cord-clamp located below the same, and a cord cutting and retaining 15 knife located below the clamp.
6. In combination with the movable plate carrying the tying-shaft, the arm or jaw M, connected to and operated by said plate.
7. The combination of the rotary tying-head, 20 the arm M, and yielding arm N, both located beneath the head, and adapted and arranged to clamp both parts of the applied band at the same time.
8. The combination of the rotary knife, having a plurality of arms or blades, and the actuating-arm arranged to rotate in one direction only, and to act directly upon the arms of the 25 knife, as described and shown.
9. In combination with the binder-arm and 30 its finger T, the rod b, spring c, and fixed arm e.
10. In a rotary knot-tying device, the combination of two tying-fingers, the first one seated in the second, and the second provided with a groove to receive the first, and with a depression or recess on one side, to receive the 35 ends of the cord as the loop is drawn off from the ends of the fingers, as described and shown.
11. A tension device for binding-machines, 40 consisting of an extended surface to sustain the cord, and an elongated flattened spring arranged to bear lengthwise, and for a considerable distance directly upon the cord, said spring being free at one end, but having the receiving end curved gradually upward and secured rigidly to an elevated support, in the 45 manner shown and described, whereby the entrance of knots and excessive enlargements beneath the spring is facilitated, sudden strains and shocks upon the cord prevented, and a substantially uniform tension produced. 50
12. The tension device consisting of the elongated bearing-surface, the flat elongated spring having one end curved gradually upward and secured to an elevated support, and the adjusting device bearing upon the spring, as 55 shown.

CHAS. L. TRAVIS.
